Term of patent 7 years

Int. Cl. D14—03

U.S. Cl. D56—4 D

FIG. 5

FIG. 1

FIG. 1 is a front and right side perspective view of a combined television receiver and battery case, showing my new design;

FIG. 2 is a fragmentary front and right side perspective view;

FIG. 3 is a fragmentary right side, top and rear perspective view;

FIG. 4 is a fragmentary left side elevational view, the opposite side being substantially a mirror image thereof; and

FIG. 5 is a fragmentary bottom plan view thereof. The battery case has been omitted from FIGS. 2, 3, 4 and 5 for convenience in illustration.

I claim:

The ornamental design for a combined television receiver and battery case, as shown and described.
